UNITED STATES PATENT OFFICE.

EINAR WINHOLT, OF ALPHA, ILLINOIS.

CONDENSER AND FEED-WATER HEATER.

1,052,988.

Specification of Letters Patent. Patented Feb. 11, 1913.

Application filed June 13, 1912. Serial No. 703,493.

To all whom it may concern:

Be it known that I, EINAR WINHOLT, a subject of the Kingdom of Denmark, residing at Alpha, in the county of Henry and

5 State of Illinois, have invented certain new and useful Improvements in Condensers and Feed-Water Heaters, of which the following is a specification.

10 My invention relates to combined condensers and feed water heaters and has for its object to provide an improved condenser which is adapted to be connected to the exhaust pipe of a steam engine for the purpose of utilizing the escaping steam to heat 15 the feed water.

Further objects and advantages of my invention will be apparent as the description proceeds.

In the accompanying drawings, Figure 1 20 is a front elevation partly in section. Fig. 2 is a top plan view partly broken away.

Referring more specifically to the drawings 5 represents a condenser comprising a top 6 and bottom 7 having peripheral flanges 25 8 and 9 respectively. A plurality of vertically arranged angle irons or plates 10 extend between the top and bottom of the condenser and are connected at their lower ends to bottom by bolts or other suitable fastening means 11 passing through flanges 12. These angle plates are preferably arranged in the form of two concentric circles, each of the plates of the outer circle being secured 30 to two of the plates of the inner circle by means of spacing bolts 13. The plates of each circle overlap and are oppositely disposed with respect to the plates of the other circle, thus the vertical spaces 14 between the adjacent plates are more or less ob- 35 structed for a purpose hereinafter described.

40 15 designates the exhaust pipe of a steam engine (not shown) projecting through the bottom of the condenser, and discharging centrally into the partially inclosed space within 45 the concentric circles of angle plates 10.

Cold water is fed to the condenser by means of a pipe 16 connected at one end to a suitable source of supply (not shown) and

at the other end to the upper end of a perforated pipe 17 the lower closed end of 50 which is provided with a conical shaped deflector 18.

In operation the exhaust steam from the engine entering the condenser comes in contact with the air cooled angle plates 10, 55 condenses and drops down upon the bottom 7 and from there flows through pipe 19 into the feed water tank for the engine (not shown) any surplausage escaping through overflow pipe 20. Simultaneously with the 60 operation just described the valve 21 in pipe 16 is automatically or otherwise operated to admit cold water to the perforated pipe 17. The cold water spouts radially from the perforated pipe as will be readily understood, 65 cooling the steam and condensing plates 10 by contact therewith and consequently greatly facilitates condensation.

From the foregoing it will be apparent that by the combined action of the air and 70 water circulating through the condenser an extremely effective means is provided for utilizing the condensed steam to heat the feed water.

Having thus described my invention, 75 what I claim is:

1. In a device of the character described, a condenser comprising a top and a bottom, a plurality of vertically extending angle plates extending between said top and bottom, said angle plates being arranged in spaced concentric circles, the plates of one circle being oppositely disposed with respect to the plates of the other circle and the adjacent plates of a circle being spaced apart, 80 means connecting the top of the condenser with a supply of cold water, means connecting the bottom of the condenser with the exhaust pipe of a steam engine, and means connecting said bottom with a feed water tank. 90

2. In a device of the character described, a condenser having a top and bottom and open sides, plates extending between said top and bottom, said plates having staggered air spaces therebetween, pipe connections 95 between the bottom of the condenser and the

exhaust pipe of a steam engine and with a feed water tank, a perforated pipe having its upper end extending through the top of the condenser and at its lower end provided
5 with a conical deflector plate, and means for introducing cold water into said perforated pipe.

In testimony whereof I affix my signature in presence of two witnesses,

EINAR WINHOLT.
